UNITED STATES PATENT OFFICE.

HENRY WILLIAM SEW HOY, OF DUNEDIN, NEW ZEALAND.

DESIGN FOR A GRAMOPHONE STAND OR SIMILAR ARTICLE.

Application filed March 27, 1926. Serial No. 17,086. Term of patent 3½ years.

To all whom it may concern:

Be it known that I, HENRY WILLIAM SEW HOY, subject of King George V of Great Britain, residing at 40 Dowling Street, Dunedin, Otago, in the Dominion of New Zealand, have invented a new, original, and ornamental Design for Gramophone Stand or Similar Article, of which the following is a specification, reference being had to the accompanying drawing, forming a part thereof, in which—

The figure represents a perspective view of the article showing my new design.

I claim—

The ornamental design for a gramophone stand or similar article as shown.

In testimony whereof I have hereunto set my hand.

HENRY WILLIAM SEW HOY.
